UNITED STATES PATENT OFFICE.

OLIVER H. CLARK, OF PITTSBURG, PENNSYLVANIA.

RAILROAD-CROSSING GATE.

SPECIFICATION forming part of Letters Patent No. 396,072, dated January 15, 1889.

Application filed January 24, 1884. Renewed July 3, 1888. Serial No. 278,956. (No model.)

To all whom it may concern:

Be it known that I, OLIVER H. CLARK, of Pittsburgh, in the county of Allegheny and State of Pennsylvania, have invented a new and useful Improvement in Railroad-Crossing Gates; and I do hereby declare the following to be a full, clear, and exact description thereof, reference being had to the accompanying drawings, forming part of this specification, in which—

Figure 1 is a side elevation of a standard and oscillating barrier of a railroad-crossing gate containing my improved automatic devices for operating the barrier. Fig. 2 is a view of the weight-standard. Fig. 3 is a side elevation of the main standard, Fig. 1, a portion of the casing being removed, and shows the position of the parts when the barrier is down. Fig. 4 is a vertical section on the line $x x$, Fig. 6, looking in the direction of the arrow. Fig. 5 is an end elevation looking in the direction of the arrow in Figs. 1 and 3. Fig. 6 is a plan view of the parts below the line $y y$, Fig. 4, the wheels which support and operate the barrier being removed. Fig. 7 is a perspective view of the operating-wheels from the right-hand side, Fig. 5, showing their relative position to the stop or escapement mechanism, some parts of which have been omitted for the sake of clearness of illustration of the more essential parts.

Like figures of reference indicate like parts in each.

Stated generally, the characteristics of this construction are as follows, viz: the barrier is mounted on a loose shaft and is provided with a counter-weight, which balances it. Two weights are employed, one to raise and the other to depress the barrier. Mounted loosely on the shaft, on each side of a central wheel keyed to the shaft, are two wheels or pulleys which are acted on in opposite directions by the weights. The central wheel has two pawls, one on each side, extending in opposite directions and ninety degrees apart, which engage ratchet-teeth on a pair of intermediate wheels, and are designed to connect the loose barrier-shaft with the weight-pulleys alternately, to effect the alternate lowering and raising of the barrier. The intermediate wheels are each provided with a pawl which engages with a ratchet-rack on the periphery

of the adjacent weight-pulley, said pawls and ratchets extending in opposite directions. The weight-pulleys are controlled by stops acting on the intermediate wheels, which stops are operated by an escapement-movement, which in turn is controlled by an electro-magnet included in an electric circuit, which may be operated from any desired point.

To enable others skilled in the art to make and use my invention, I will now describe it by reference to the drawings.

Referring now to the drawings, I will state that Fig. 1 shows but one standard and barrier. Usually there are two or four standards and barriers at each crossing. The barriers extend across the road or street alongside of the track. The operating mechanism is contained in one standard, called the "main standard," and the barriers of the other standards are operated from the main standard by ropes, chains, shafting, and gearing, or other power-connections extending between them underground. It is unnecessary for the purpose of this case that the other standards be shown, and I have therefore omitted all but the main standard.

The main standard 1 consists of a box or casing, 2, having a removable cap, 3, and bosses 4, to afford bearings for the shafts contained therein. The main shaft 5 is loose in its bearings, so as to turn freely, and its ends extend beyond the sides of the casing 2, so that the rear or bifurcated end of the barrier 6 may be keyed thereto, as shown in Fig. 1. The barrier 6 is provided with counter-weights 7, which are heavy enough to balance the long front end.

Referring now to Fig. 5, there is keyed to the shaft 5 a central wheel, 8, which is provided with grooves 9 for the ropes or chains which actuate the barriers of the companion standards. At the sides of the wheel 8 are two wheels, 10 and 11, called "intermediate wheels," which are of less diameter than the wheel 8 and are loose on the shaft 5. Wheel 10 is provided on its periphery with four ratchet-teeth, 12 12' 12² 12³, and wheel 11 has a like number of ratchet-teeth, 13 13' 13² 13³, running in the opposite direction; and on opposite sides of the wheel 8, beyond the edges of the wheels 10 11, are the pawls 14 and 15, which extend in opposite directions and en-

gage the ratchet-teeth, the pawl 14 engaging the teeth on the wheel 10 on the left side of the wheel 8, and the pawl 15 the teeth on the wheel 11 on the right side. Also mounted loosely on the shaft 5, outside of the wheels 10 and 11, are the combined ratchet and pulley wheels 16 17, the grooves 18 and 19 of which receive the ropes or chains of the actuating-weights, and of which the ratchet-racks 20 and 21 engage the pawls 22 and 23, pivoted on the sides of the wheels 10 and 11, and, like the teeth of the racks 20 and 21, extending in opposite directions. The pawl 22, on the left side of the wheel 10, engages the rack 20, and the pawl 23, on the right side of the wheel 11, engages the rack 21. The wheels 10 and 16 move from left to right, being so actuated by the weight attached to the chain 24, and the wheels 11 and 17 from right to left, being so actuated by the weight attached to chain 25, and the wheel 10, when moving, must turn the wheel 8 in like direction, and wheels 10 and 16 are loose on the shaft 5. The ratchet-teeth, rack, and pawls are arranged to connect the wheels 10, 16, and 8 together when the wheel 16 moves, so that they all move together. The same is also true of the wheels 11 and 17, their ratchet-teeth, and pawls, which are moved in the opposite direction by the chain 25. The pawls 14 and 15 and the pawls 22 and 23 are respectively provided with springs 26 and 27, to hold them in contact with the ratchet-teeth and racks. Lugs 77 77 are provided on the inside of the case to trip the pawls 14 and 15. These lugs are so placed in the path of the pawls that they strike the ends of the latter at the proper moment to raise said pawls, and thus effect the alternate release of the central wheel, 8, from the respectively-moving wheels standing on its opposite sides.

I will now describe the escapement-movement, consisting of two parts, which I will designate "primary" and "secondary" escapements.

Referring to Fig. 3, which is a side view of the mechanism showing all the operative parts relating to the right-hand side of the same, and all that relate to the closing of the barrier, which in the drawings is supposed to be closed, and also referring to Fig. 7, which is a perspective of most of the devices shown in Fig. 3, on a suitable support, 28, is an electromagnet, 29, which is arranged in the circuit 30, Fig. 1, of a suitable battery, 31, and is provided with a vibrating armature, 32, the upper end of which is flattened, as at 33, to afford alternately a support for the inner ends of two levers, 34 and 34', arranged opposite to each other. The lever 34, counterweighted at its outer extremity, so as to reduce to a minimum the weight upon the armature-lever 32, is rigidly mounted on a shaft, 35, which has its bearings in a standard, 36, and a strap, 37. Rigidly attached to the shaft 35 are other arms or levers, 38 and 39. Extending from the opposite side is an arm, 40, which is

weighted at 78 near its outer end and keyed to a shaft, 41. The outer end of the arm 40 rests on a pivoted stop, 42, mounted in a slot 70 in the arm 39, which stop is incapable of downward movement, but may be turned upward. If turned upward, it is immediately restored to position, as in Fig. 3, by a spring, 43, arranged behind it for that purpose; also 75 keyed to the shaft 41 are two other arms, 44 and 45, the functions of which will be explained.

At the right side of Fig. 3 is a shaft, 46, having its bearing in one of the bosses 4, Fig. 80 1, and in the cross-bars 47 and 56, Fig. 6, and keyed to it is an arm, 48, which extends across the standard, and at its outer end has a cross-pin, 49, which rests on a stop, 50, mounted on the swinging arm 51. The stop 50 has a spur 85 resting against a stop, 52, Fig. 3, which prevents its downward movement, but it can swing upward. It is restored to its normal position (shown in Fig. 3) whenever swung upward by a spring, 53, placed back of it, 90 Figs. 6 and 7. The arm 51 and the arm 54 are keyed to the shaft 55, which has its bearings in a boss, 4, and the cross-bar 56, Fig. 6. On the face of the arm 54 is a projection or catch, 74, and secured to the shaft 41, Figs. 3 and 6, 95 is a short arm, 73, which, when the parts are in their normal position, fits over the catch 74 and prevents the arm 54 and its shaft 55 from turning, so as to hold the arm 51 in position to support the outer end of the radial arm 48. Keyed to the shaft 46 are two rocking arms, 57 and 58. (Shown in dotted lines in Fig. 3 and in full lines in Fig. 6.) Pivotedly connected to the arm 57 is a stop or pawl, 59, having a guide-pin, 60, which projects laterally therefrom into the guide-slot 61, Fig. 3, in the cross-bar 56. Connected in like manner to the arm 58 is a stop or pawl, 62, having a guide-pin, 63, which projects laterally therefrom into a guide-slot, 64, also in the cross-bar 56. The ends of the stops or pawls 59 and 62 are square, so as to engage with the teeth on the intermediate wheel, 11.

Pivoted loosely on the shaft 67, which is journaled in the cross-bar 56, is a hook, 65, 115 which acts, in conjunction with a projection, 66, on the arm 40, Fig. 3, to support the latter at certain times in the operation, as shown in Fig. 3, and keyed to the shaft 67 is an arm, 68, which projects down past the left side of 120 a pin, 69, on the hook 65. Also keyed to and rising vertically from the shaft 67 is an arm, 70, which stands in the path of a pin, 71, Fig. 3, on the side of the center wheel, 8, so as to be struck by the pin as the wheel 8 turns, and 125 thereby cause the shaft 67 to turn and the arm 68 to strike the pin 69 and force the hook 65 backward, so that it shall no longer support the arm 40. Back of the hook 65 is a spring, 72, which bears against the hook and 130 restores it to its normal position. (Shown in Fig. 3.)

I will now describe the operation of the devices as they act when the barrier 6 passes

from a vertical or open position to a horizontal or closed position, the latter being the one shown in the drawings. The gate is closed by releasing the wheels, so that the weight 5 25, Fig. 5, shall be free to descend. Before the descent began the tooth 13 at the top of Fig. 3 occupied the position of the tooth 13' at the right of the figure, the stop 62 of the escapement mechanism withdrew from the 10 path of the tooth 13', which then stood at the lowest point, and the stop 59 was thrown forward into its path; the weight-pulley 17 then turned in the direction of the arrow, Fig. 3, and being connected to the center wheel, 8, 15 by means of the rack 21, pawl 23, wheel 11, tooth 13, and pawl 15, turned it through an arc of ninety degrees, bringing it to the position shown in Fig. 3, lowering the barrier. It will be remembered that stops 62 and 59 are 20 pivotally connected to the arms 57 and 58, secured to the shaft 46, to which shaft is keyed the arm 48, controlled by the escapement mechanism, and consequently while the arm 48 is held by the mechanism the stop 62 prevents 25 the movement of wheel 11; but when the arm 48 is released then stop 62 recedes and is lifted out of the ratchet-tooth by cam slot or guide 64, while stop 59 advances into the path of the ratchet-tooth, and in its turn is forced 30 back and lifted out of the ratchet-tooth by its cam slot or guide 61. The recession of the stop 59 rocks the shaft 46 and brings stop 62 up to the periphery of wheel 11 after the ratchet-tooth has passed and in time to engage with the following ratchet-tooth. With 35 this general description of the operation of the stops 59 and 62, I will further describe the operation of the escapement mechanism which controls the stops. The release of the tooth 40 13' of the wheel 11 from the stop 62, which was necessary in order to permit this partial revolution of the wheels, was effected as follows—viz: a current was sent through the magnet 29, attracting the armature 32, and 45 thereby withdrawing the support from the outer end of the arm 34 and permitting it to descend, either by reason of its own weight and the weight of the arm 38, or by reason of the pressure of the arm 40 on the catch 50 42. This, causing the shaft 35 to turn, caused the arms 38 and 39 also to swing backward, withdrawing the support 42 of the outer end of the arm 40 and permitting it to fall, the arms 44 and 45 moving with it, the 55 three arms 40, 44, and 45 being keyed to the shaft 41. The turning of the shaft 41 causes the short arm 73 to rise off the catch 74 and release the arm 54. The arm 45 coming in contact with arm 54 causes it and the arm 51, 60 both being keyed to the same shaft 55, to swing backward, thereby withdrawing the support 50 from the outer end of the arm 48 and releasing the shaft 46, which is held from turning so long as the arm 48 is held by the 65 catch 50. Then the stop 62, being no longer supported, yields to the pressure of the weight 25, acting through the wheel 11 and tooth 13', and is pressed backward, its pin 63 moving in the guide 64 until the tooth 13' has cleared it and passed on. The pressure on the stop 62, acting through the arm 58, turns the shaft 46 and throws the arm 57 forward, so as to 70 press the arm or stop 59, guided by the pin 60 and slot 61, into the path of the tooth 13'. As the wheel 8 is carried by the wheels 17 75 and 11 from right to left through an arc of ninety degrees, as indicated, the pin 71, passing through the same distance, takes its position, as shown in Fig. 3, at the right of the arm 70. In so doing it first presses the arm 80 70 backward and out of its path, at the same time throwing the lever 68 away from the pin 69, so that the hook 65 will not be disturbed or the arm 40 allowed to drop from its support thereon during such movement of the 85 wheel 8. As the arm 48 falls, the inner end of the pin 49 comes into contact with the rear side of the portion 75 of the arm 44 and forces the arm 44 forward, causing the shaft 41 to turn in the same direction and thereby 90 to raise the arm 40. The lifting of the arm 40 causes the lowering of the arm 73, so that the recess in the latter passes back of the projection 74 on the arm 54, thereby preventing the shaft 55 from accidentally turning, 95 and insuring the support of the arm 48 until such time as it is designedly released. The portion 75 of the arm 44 is long enough to cause the travel of the pin 49 on it to restore the arms 40, 44, and 45 to their normal positions, as shown in Fig. 3. The part 76 of the arm 44 corresponds with the arc described by the inner side of the pin 49. The latter having passed over the part 75, and thereby raised the arm 40 to its position above the hook 65, 100 then passes along the part 76, sustaining the arm 40 in its position until the hook 65, which is loosely pivoted, having been previously released by lever 68, recovers its place under the projection 66. As the arm 40 rises, it 105 encounters and raises the arm 38, Fig. 3, and with it the arms 34 and 39, but it does not at once fall back to and rest upon the support 42, for it is supported by the hook 65 slightly above the support 42, and the arm 34 is sustained 110 slightly above the level of the top of the armature 32. During this stage of the operation the parts constituting the secondary escapement, consisting of the arms 34 38 39 40 44 45 73 and hook 65, are all restored to place; and it now 115 remains to show how the primary escapement, consisting, with the exception of the hook 65, of the parts supported by cross-bar 56, is restored to its normal position. The revolution of the wheel 11 causes the tooth 13' to 120 come in contact with and press against the end of the arm or pawl 59, forcing it back out of the way in the slot 61. This movement of 59 turns the shaft 46, raising the arm 48 and throwing the arm or pawl 62 forward into its 125 normal position in the path of the tooth 13'. As the arm 48 comes up, its pin 49 forces the pivoted stop 50 back out of the way and passes it, and then the stop falls back into 130

position under the pin and supports the arm 48. This completes the operation of the parts shown in Fig. 3, and the wheels continue to move until they have made a quarter-turn, 5 when the tooth 13² comes in contact with the stop 62, and then their movement is stopped and the barrier is down, or in a horizontal position, as shown in Fig. 1. Immediately before the arrest of the wheels, as stated, the 10 barrier, Fig. 1, cushions upon a spring, 79, so as to prevent sudden strain caused by the jar upon the arm 62 or its connected parts. In like manner when the barrier is brought to a vertical position it first cushions against the 15 spring 80, retarding the movement of the rotating wheels, which are finally arrested by the stop 62'. The barrier is raised again by the operation of the devices on the opposite side of the main or center wheel, 8. These 20 devices are duplicates of the parts shown in Fig. 3, and are marked with the same reference-numbers, but are distinguished therefrom by the *primus* character.

As has been previously stated, the pawls 14 25 and 15 are never both engaged with the ratchet-wheel at the same time, but alternately, one pawl being released by its cam 77 at the instant the other pawl is ready to engage.

30 Referring to Figs. 3 and 4, and tracing the operation of the parts, it will be noted that when pawl 15 was on the right, in the position where tooth 13² is now represented, the spring 26 held it in engagement with tooth 13², and 35 wheels 11 and 8 moved together from right to left in the direction of the arrow and under force of weight attached to chain 25, until they reached the position shown in the figures, when cam 77 trips the pawl 15 and releases 40 the wheel 11, which is then held by stop 62. It will also be seen that when the pawl 15 arrives at the position shown the pawl 14, moving in like direction, through a like distance, arrives in front of the tooth 12². 45 When the stop 62' is withdrawn and the wheels 10 and 16 are permitted to rotate, as described, the pawl 14, resting against the tooth 12², carries the wheel 8 back to its original position, when the tang of the pawl 15 50 is pressed down by the spring 26 and the pawl 15 arrives in front of the tooth 13². The central wheel is again carried from right to left in direction of the arrow, the pawl 15 up- 55 permost, when wheels 11 and 17 are permitted by the action of their escapement to make another partial revolution to the left. The action of the escapement in the latter case implies the closing of the barrier and is consequent upon the attraction of the armature 32, as has been fully described. The raising 60 of the barrier, or the reverse movement of the wheel 8, follows the rotation of the wheels 10 and 16 to the right, and in turn implies the operation of their escapement (marked *primus*) and is consequent upon the retraction 65 or opposite movement of the armature 32. The parts in Fig. 3 remain in the position shown

therein so long as the electric current is passing through the magnet 29, and while such is the case the armature 32 is held in contact 70 with the core of the magnet and supports the arm 34', as shown in Fig. 4.

When it is desired to open the gate or raise the barrier, the circuit to the magnet is opened and then the armature 32 is retracted by its 75 spring and comes into a supporting position under the arm 34. Its withdrawal from under the arm 34' permits the latter to fall and the escapements marked *primus*, on the left side of the standard, Figs. 4 and 6, to act in the 80 same manner as has been described with relation to the right-hand escapements in Fig. 3. This releases the weight-pulley 16, which, being actuated by the weight 24, turns from left to right, as indicated by the arrow marked 85 thereon in Fig. 5, and carries with it the intermediate wheel, 10, and the main wheel 8. As the latter turns back, the projection 71, Fig. 3, strikes the upper end of the arm 70 and throws the hook 65 backward, letting 90 the arm 40 fall down to the support 42 and the arm 34 onto the upper end of the armature 32. The escapement shown in Fig. 3 is then ready to act whenever the electric current is again sent through the magnet to withdraw 95 the armature from under the arm 34. The other (or *primus*) escapement acts in precisely the same way, except that it is released by opening the circuit to the magnet, instead of closing it thereto.

100 It only remains to state that when it is desired to close the barrier 6 a current is sent through the magnet from the block or signal house or other place where the circuit-closer is located, and that it is raised by opening the circuit. I have spoken of the circuit-closer being placed in and operated from a station-house, but I will add that the circuit may be closed and opened automatically by a passing train by the use of any of the constructions 105 heretofore devised for railway-signaling suitable for the purpose.

In Fig. 2 I show the post or standard 81, which contains the actuating-weights 82 83, which move in a vertical opening, 84. The 110 weight 82 is connected to the ends of the chain 25, which extends to the top of the post, and thence by sheaves 85, 86, and 87 to and around the pulley 17, and thence by sheaves 88 and 89 back to the weight 82. The other 115 weight, 83, is connected to the chain 24, which passes over the pulley 16, and is extended in the same manner by means of similar sheaves. Reels 90 91 are provided in the post 81 for raising the weights 82 83. The cords or chains 120 92 extend from the grooves 9 of the central wheel, 8, to other standards, where they cause the barriers to move in unison with barrier 6.

125 The intermediate wheels are of use only in connection with the escapement or stop mechanism. So far as any advantage in their use as connecting devices is concerned, they may be dispensed with and the pulley-wheels be connected directly to the central wheel, 8, by

reversely-extending racks and pawls. The intermediate wheels, 10 11, are of use when a stop mechanism or escapement is employed to prevent the movement of the pulley and 5 weights, except when it is necessary to effect the opening or closing of the gate. The stop mechanism cannot be applied directly to the central wheel for the reason that said wheel has to move in both directions, and at each 10 movement the stop mechanism must be holding one or the other of the pulleys from turning. The pulleys are made of much smaller diameter than the central wheel, so that the fall of the weights necessary to effect the oscillation of the barriers may be small, and thereby obviate the necessity for frequent 15 raising of the operating-weights.

My invention has its advantages in the fact that by it crossing-gates can be operated from 20 a station at any desired distance away, or, as stated, automatically by the passing trains, thereby doing away with gatemen, or, if desired, putting the operation of any desired number of gates in the care of one person in 25 a central station, as in the case of a freight-yard crossed by several streets.

The hereinbefore-described invention is an improvement on that granted to me in Letters Patent No. 307,098, dated October 28, 1884.

30 What I claim as my invention, and desire to secure by Letters Patent, is—

1. In a railroad-crossing or similar gate, the combination of an oscillating barrier, a wheel secured to the shaft of the barrier, two loose 35 clutch-wheels, one on each side of the fixed wheel, and having reversely-arranged pawl, ratchet, and trip mechanism, locking-stops for each clutch-wheel, and the escapement mechanism, substantially as described, for actuating 40 the stops, whereby the barrier may be both raised and lowered by pulleys and weights, substantially as and for the purposes specified.

2. In a railroad-crossing or similar gate 45 having an oscillating barrier with a fixed wheel on its shaft, and a loose clutch-wheel, the combination therewith of a shaft, 46, having two arms or cranks, 57 and 58, stops or pawls 59 and 62, pivoted on said arms, an arm or lever, 48, secured to and extending transversely 50 from the shaft, a support, 51, and suitable mechanism for tripping the support 51, substantially as and for the purposes specified.

3. In a railroad-crossing or similar gate 55 having an oscillating barrier with a fixed wheel and loose clutch-pulleys on its shaft,

and having a rocking arm with locking stops or pawls, the combination therewith of a vibrating arm or lever attached to the rock-shaft of the pawls, a support for the free end 60 of the vibrating arm or lever, and a second vibrating lever, 40, controlled by a trip, and an arm, 73, on the shaft of the last-mentioned lever, which controls the support or trip of the first-named vibrating arm or lever, substantially as and for the purposes specified. 65

4. In a railroad-crossing or similar gate having an oscillating barrier with a fixed wheel and loose clutch-wheels on its shaft, a rock-shaft with pawls or stops, a vibrating 70 arm for controlling the rock-shaft, a trip, and a second vibrating arm, 40, for controlling the first trip, 51, the combination therewith of a second trip, 34 42, operated by the armature of an electro-magnet, substantially as and for 75 the purposes specified.

5. In a railroad-crossing or similar gate having an oscillating barrier with a fixed wheel and loose clutch-wheels on its shaft, a rock-arm with pawls or stops, trips, and vibrating levers for operating the trips, the combination therewith of a hook, 65, and a trip, 68 and 70, operated from the fixed wheel 8 of the shaft, substantially as and for the purposes specified. 85

6. In a railroad-crossing or similar gate having an oscillating barrier with a fixed wheel and loose clutch-wheels on its shaft, a rock-arm with pawls and trips, the combination therewith of a tappet, 45, and a cam-arm, 90 44 75 76, keyed to the shaft of a vibrating lever, 40, and a pin on a rock-arm, 48, whereby the rock-arm is caused to operate the lever 40, substantially as and for the purposes specified. 95

7. In a railroad-crossing or similar gate having an oscillating barrier with a fixed wheel and loose clutch-wheels on its shaft, and rock-shaft and pawls, the combination therewith of an escapement mechanism consisting of the vibrating arm 48, trip 51 54, 100 vibrating arm 40 73, tappet 45, cam-arm 44, hook 65, trip 68 70, fixed wheel 8, trip 34 42, and an electro-magnet and its armature, substantially as and for the purposes specified. 105

In testimony whereof I have hereunto set my hand this 18th day of January, A. D. 1884.

OLIVER H. CLARK.
